(57) **CLAIM**

The ornamental design for a level cable spacer rod as shown and described.

DESCRIPTION

FIG. 1 is a perspective view of a level cable spacer rod in accordance with the present invention.

FIG. 2 is a top view thereof; the bottom view being identical; and,

FIG. 3 is a front view thereof; the rear view, left view, and right view being identical.

The level cable spacer rod is shown with a symbolic break in its length. The appearance of any portion of the level cable spacer rod between the break lines forms no part of the claimed design.
